LIQUID LEVEL CONTROL FOR WELL PUMP-
ING APPARATUSClarence N. Scott, Houston, Tex.; Bertha Britton
Scott, administratrix of estate of said Clarence
N. Scott, deceased

Application July 24, 1937, Serial No. 155,359

11 Claims. (Cl. 103—203)

My invention relates to well pumping apparatus for raising the fluid in bored wells from the pumping depth in the well to the surface of the ground.

It has particular but not exclusive relation to that class of such apparatus known as sucker-rod pumps or working-barrels.

The fluid entering such bored wells from the producing formation contains more or less gaseous fluid and the aim is to as far as possible separate in the well this gaseous content from the liquid and prevent its getting into the pump along with the liquid.

The liquid to be raised is conveyed to the pump cylinder or barrel by an intake pipe (usually called perforated pipe) attached to the bottom of same and submerged in the liquid in the well bore. It is so arranged that gas released from the fluid on entering the well bore is permitted 15 to escape to the surface of the ground through the annular passage formed between the suction pipe, working barrel and discharge tubing perimeters and the inside surface of the well casing.

When properly constructed, these pumps can 25 draw in and will discharge on each cycle fluid of high gas content and will not become gas-bound or gas-locked until the gas content of the intake fluid per stroke closely approaches 100% of the intake stroke displacement of the piston 30 or plunger.

When selecting the size and speed of pump or working barrel to be installed, the aim is to have its plunger or piston displacement excessively large to insure getting the full production of oil 35 that the well is capable of drawing from the producing formation.

In practical operation this works out about as follows: On each cycle of the pump plunger or piston (one up and one down stroke) more liquid 40 is pumped from the well than comes into it from the producing formation during that period of time and consequently the level of the liquid in the well bore is lowered a little by each succeeding cycle until the uppermost perforation in the 45 intake pipe (perforated pipe) or the open lower end of the unperforated intake pipe is uncovered by the lowered liquid level in the well. The area so uncovered and thus exposed to gas or air intake, while actually small, is nevertheless sufficient to instantly admit enough gas or air to the intake pipe and pump working chamber to drop the liquid from same (lose its suction) and the working chamber fills with gas or air and thus becomes gas-locked and the pump idles and 55 will not draw in any more gas or air or any more

liquid nor discharge any until the liquid level in the well has built up in elevation very considerably. This is repeated continuously and my invention has as an object to prevent such operation.

The more excess pumping capacity, over and above that actually required to pump the potential production, that is provided the oftener suction is uncovered to gas or air and the higher the average bottom-hole pressure will be and 10 the less will be the oil production of the well.

Production of fluid of an oil well, other things being equal, varies between maximum production when bottom-hole pressure is entirely removed and zero production when bottom-hole pressure 15 is entirely removed and zero production when bottom-hole pressure is at its maximum and equals stabilized formation pressure.

It will be seen that bottom-hole pressure instead of being maintained continuously at the 20 minimum with the corresponding maximum production of liquid, is in reality, with pumping apparatus as at present in the use and as operated, an average between the minimum bottom-hole pressure just before the liquid level uncovers the 25 intake perforation and a very considerable built-up maximum bottom-hole pressure at the end of the gas-locked idling period.

Had it been practicable to slow the pump down just before the liquid level uncovered the perforation or open end of the intake pipe so that its speed and capacity thereafter corresponded identically with the potential liquid production of the well at that liquid level and bottom-hole pressure, the pump would not have lost its suction and become gas-locked but would have continued full liquid displacement and discharge and bottom-hole pressure would have been maintained continuously at that low liquid level elevation and maximum production of oil would 40 have been realized.

The same result would have been secured if, instead of slowing the speed of the pump down as proposed in the preceding paragraph, its liquid-discharging capacity had been reduced in 45 some other manner to conform to the potential liquid production of the well and prevent the pump from losing its suction and becoming gas-locked.

It will be apparent that any regulation or control of the liquid discharging capacity of the pump, to adjust said capacity to the rate of production of liquid from the producing formation into the well bore at any predetermined minimum liquid level elevation or bottom-hole pres- 50 55

sure in the well to prevent uncovering of the pump intake to gas or air and the consequent gas-locking of the pump, must be automatic and be actuated or controlled or both by liquid level 5 in the well bore which determines bottom-hole pressure.

An object of my invention is to provide regulating or controlling means which will automatically prevent liquid level in the well bore or casing 10 from uncovering the pump suction to instantly admit gas or air in such quantity as to cause the pump to lose its suction and become gas-locked with its resulting idling and the consequent excessive building-up of liquid level in the 15 well with the corresponding material increase in bottom-hole pressure.

Another object is to provide regulating and controlling means which will automatically maintain liquid level in the well bore or casing at a 20 predetermined elevation with comparatively small variation in said elevation and thus prevent it from building up or increasing in elevation with the resulting increase in bottom-hole pressure and consequent reduction in the production of liquid flowing from the producing formation into the well.

Another object is to provide a method of operating bored wells which will maintain the maximum oil production by automatically maintaining the minimum bottom-hole pressure in same. 30

In the drawing herewith:

Fig. 1 is a central longitudinal section through the lower portion of a well installation embodying one form of my invention in which I use a fine 35 or narrow vertical regulating slot preferably in plural sections with supporting bridges.

Fig. 2 is a similar section but shows an alternative construction in which I use a cleaning device to keep the narrow regulating slot open and 40 free from obstructions.

Fig. 3 is a similar section and shows another construction in which I use small frusto-conical regulating perforations disposed in vertical spacing, instead of the slot shown in Figs. 1 and 2.

Fig. 4 is another similar section and shows another construction in which I use frusto-conical regulating perforations as in Fig. 3, but they are 45 larger and are equipped with a cleaning device which keeps them open and free from obstructions and at the same time reduces the gas or air-passing area to the required small net.

Like parts shown in the several figures have the same reference numbers.

1 is the fragmentary lower end of the sucker-rod pump or working barrel as is at present in general use. 2 is the standing valve (suction) assembly in the said pump. 3 is the suction or intake pipe of the pump. I have shown it with the regular large perforations 4 as at present in general use in standard perforated pipes. One of these perforations is sufficiently large to admit enough gas or air to the pump to equal full plunger displacement and cause it to become gas-locked, when said perforation is uncovered by 60 liquid level in the well.

5 is a portion of the suction or intake pipe of the pump which has incorporated with it my regulating or controlling device. It connects 65 with the lower end of the pump or working barrel and is coupled to the suction or perforated pipe 3 by coupling 6. Or, suction pipe 3 may be omitted and liquid may enter through the open lower end of coupling 6. Or, the coupling 6 may be substituted by a strainer 7 as shown in Fig. 4. Or,

the suction pipe 3 and the portion 5 may be combined and coupling 6 omitted as shown in Fig. 3.

8 is a regulating or controlling slot in the intake pipe. It increases in width from the perimeter of the pipe to the inside surface of same 5 to prevent lodgment of obstructions. Its width at the perimeter of the pipe is narrow and its gas or air passing area is small so that even if uncovered by liquid level its entire length it will not pass enough gas or air to cause the pump to become gas-locked. As shown in Fig. 3, small perforations may take the place of the slot 8. In this figure, 9 are regulating or controlling frusto-conical perforations shown in a single vertical row. Their combined gas or air passing area is 15 small so that liquid level uncovering even all of them will not pass sufficient gas or air to gas-lock the pump.

Also, I may employ means to clear the slots 8. In Fig. 2, 10 are fins or scrapers which travel in 20 the regulating slot 8 to keep this narrow slot open and free from obstructions. They may be formed on or attached to bar 11 which is hinged on links 12 on pins 13. 14 is a liquid-impact-propelling plate on bar 11. It obstructs 25 the flow of liquid in the pipe 5 sufficiently to cause bar 11 and scrapers 10 to move up as the pump draws in fluid. Their weight is sufficient to cause them to fall to bottom position again as the liquid flow in the pipe intermittently ceases. Any other 30 suitable form of cleaning device may be used. I may also provide means to clear openings 15 in Fig. 4.

In this embodiment, 15 are regulating or controlling perforations similar to but larger than 35 9. They are equipped with perforation cleaning-pins 16, hinged on a supporting bar 17. These pins, in addition to keeping the perforations 15 clear of obstructions, reduce the net gas or air-passing area of same to that required so that 40 should liquid level uncover even all of them, the pump will not become gas-locked. The liquid as it flows upward in the intake pipe 5 causes these pins to move around in the perforations 15 and thus keep the fine annular openings around the 45 pins open and free from obstructions. 18 is the inside surface of the well bore, casing, or liner.

The operation of the regulating or controlling device is as follows:

The well pump is discharging, by reason of 50 its excess capacity, more liquid than is flowing into the well from the producing formation and accordingly liquid level in the well is progressively lowered in elevation until the upper end of slot 8 or the uppermost perforation 9 or 15 is uncovered by the liquid level and gas or air in small quantity is admitted to the intake pipe 5 and pump 1 and reduces the liquid-discharging capacity of the said pump by the small amount that gas or air is initially admitted. If the liquid 60 discharging capacity of the pump after its initial reduction is still in excess of the quantity of liquid flowing into the well from the producing formation, the liquid level in the well will continue to lower and uncover more of the slot 65 or another perforation thus admitting more gas or air to the pump and still further reducing its liquid-discharging capacity. Just so long as the liquid-discharging capacity of the pump (which is the total displacement capacity of the 70 piston or plunger less that portion of the displacement represented by gas or air), exceeds the quantity of liquid entering the well from the producing formation the liquid level in the well will continue to lower until the liquid-discharging 75

capacity of the pump has been finally reduced, by increased gas or air intake through the regulating slot or perforations, to equal the liquid entering the well from the producing formation, when liquid level in the well will then stabilize with perhaps small variations and the pump will then continue pumping that proportion of gas or air and liquid and maintain bottom-hole pressure at the minimum with maximum production of liquid.

In many of the installations in which my regulating device or method would be installed, plain regulating slots 8 or small perforations 9, without any cleaning device, would be used. When conditions are such that fine slots and small perforations cause trouble by stopping up, cleaning devices can be used as contemplated.

I call attention of the fact, that the energy used in compressing the gas or air content of the pump is entirely recovered in this respect, that the gas or air compressed and discharged into the discharge tubing acts as an air lift and lightens the column of liquid in the same and accordingly reduces the oil pressure against which the pump must discharge.

What I claim is:

1. A well tubing, a deep well pump, a fluid intake pipe at the lower end projecting below the operating level of the liquid in the well, a regulating section thereon spaced above and below the operating liquid level, said regulating section having inlet openings therein spaced or disposed at different levels to allow a gradually increasing inlet of gas or air to said pump, and cleaning members pivotally mounted to project loosely through said openings to restrict said openings and to clear same of material tending to clog them.

2. A deep well pump, a well tubing, a fluid intake pipe at the lower end thereof, a gas or air regulating section of said tubing spaced upwardly from a lower liquid intake pipe, said regulating section having a vertically protracted opening of restricted lateral size, arms pivotally mounted on said pipe and projecting through said opening, and means to move said arms to clear said opening.

3. A well tubing, a deep well pump, a fluid intake pipe at the lower end of said pump, a gas or air regulating section of said pipe spaced from the said lower end, said regulating section having a plurality of vertically protracted openings of restricted lateral dimension, arms pivotally mounted on said pipe and projecting through said openings, and means responsive to the movement of liquid in said pipe to agitate said arms.

4. A suction or intake pipe for deep well pumps, having liquid inlet openings in the lower portion thereof and gas or air regulating inlet openings in the upper portion thereof, said liquid openings being of ample size to prevent clogging, said gas or air openings being restricted horizontally but protracted vertically in number and dimension to progressively and gradually increase restricted gas or air admission therethrough from the initial to the final uncovering thereof by the lowering liquid level in said well, said final uncovering being always less than that required to admit the full pump displacement of gas or air.

5. A suction or intake pipe for deep well pumps, having liquid inlet openings in the lower portion thereof and gas or air regulating inlet openings in the upper portion thereof, said liquid openings being of ample size to prevent clogging, said gas or air openings being restricted horizontally but

protracted vertically in number and dimension to progressively and gradually increase restricted gas or air admission therethrough from the initial to the final uncovering thereof by the lowering liquid level in said well and means to clear said restricted openings of material tending to clog the same.

6. A suction or intake pipe for deep well pumps, having liquid inlet openings in the lower portion thereof below the desired operating liquid level in the well and gas or air regulating inlet openings in the upper portion thereof above and below the desired stabilized operating liquid level, said liquid openings being of ample size to prevent clogging, said gas or air openings being restricted horizontally but protracted vertically in number and dimension to progressively and gradually increase restricted gas or air admission and correspondingly decrease liquid admission to said pipe and pump from initial uncovering of said gas or air openings by the lowering liquid level until operating liquid level is stabilized by reduced liquid pumping capacity of the well pump by gas or air admission to equal the liquid entering the well from the producing formation.

7. A deep well reciprocating pump installation including a tubing, a standing valve therein, a perforate intake pipe at the lower end of said tubing, a regulating section in said tubing above said intake pipe and below said standing valve, said regulating section being imperforate except for a row of fine and narrowly restricted openings therein arranged in vertical direction so that when said openings are progressively exposed as the liquid level sinks in the well they will admit to said tubing a restricted quantity of gaseous fluid, gradually increasing as the liquid level is lowered until stabilized liquid level is reached and before said intake pipe is exposed.

8. A deep well pump including a well tubing for use with a reciprocating plunger, a standing valve, a liquid intake pipe at the lower end of said tubing, a gaseous fluid intake regulating section in said tubing above said liquid intake pipe, said regulating section having a horizontally restricted but vertically protracted inlet for a limited amount of gaseous fluid, which is progressively increased in quantity as the liquid level in the well is lowered to expose a greater portion of said restricted inlet opening until liquid level is stabilized.

9. In a deep well reciprocating pump, a pump tubing, a standing valve thereon, a perforated intake pipe for liquid, an upper intake section for gas or air below said standing valve, said liquid intake pipe having unrestricted inlet for said liquid, said gas or air intake regulating section being at a higher level and adapted to be exposed as the liquid level is lowered, said section having a narrow, restricted inlet for a limited amount of gas or air increasing in quantity by small graduations as the liquid level in the well is lowered by said pump, and until the liquid level is stabilized to permit the pumping of both gas and liquid corresponding with the rate of production of the well.

10. In a deep well reciprocating pump, a pump tubing, a standing valve thereon, a perforate liquid intake pipe spaced below standing valve, a gas and air intake regulating section between said valve and said liquid intake pipe, said regulating section having an opening therein for gas and air to allow a limited inlet thereto through which the inlet of gaseous fluid gradually increases as the liquid level is lowered and until it is stabilized and cleaning means loosely mounted to project

through said opening and to prevent clogging of the same.

11. In a deep well pump installation, the combination of an intake pipe extending below said pump, liquid inlet openings in the lower portion thereof, the upper regulating portion thereof being imperforate except for horizontally restricted openings progressively arranged in a vertical direction so as to admit to said intake pipe a re-

stricted quantity of gas or air gradually increasing as the liquid level in the well is lowered until the volume of liquid flowing from the producing formation into the well and the volume of liquid delivered by the well pump are equalized and said liquid level elevation is stabilized, and means to clear said restricted openings of material tending to clog the same. 5
